Inventor

UNITED STATES PATENT OFFICE

JOHN V. JANIN, OF SEATTLE, WASHINGTON

STREET MARKER

Application filed November 14, 1927. Serial No. 222,968.

The invention is a sign comprising two angularly disposed plates in which each of the plates designates, first the intersecting street and also the street upon which the observer is situated.

The object of the invention is to provide a sign for street intersections from which the observer may readily determine the names of both the streets of the intersection at a glance.

Another object of the invention is to provide a street marking sign from which one may readily determine his location upon both streets.

15 A further object of the invention is to provide a street marking sign which may readily be installed in a conspicuous location and readily read.

And a still further object of the invention 20 is to provide a street marking sign which is of a simple and economical construction.

With these ends in view the invention embodies a sign comprising two right-angularly disposed plates, and suitable straps for attaching the plates to a post or other object. Each of the plates is provided with the name of both of the intersecting streets, the length of the streets and the number of blocks from the beginning of the streets to the intersection.

30 Other features and advantages of the invention will be seen from the following description taken in connection with the drawings, wherein:—

35 Figure 1 is a view showing one of the plates.

Figure 2 is a view showing the sign as it would appear when attached to a post.

40 Figure 3 is a view showing the means of attaching the sign to a post.

Figure 4 is a view showing an alternate means for attaching the sign to a post.

45 Figure 5 is a view showing a means of attaching the signs to a corner of a building.

In the drawings the device is shown as it would be made wherein numeral 1 indicates one of the plates, numeral 2 the other plate and numeral 3 the strap by which the plates are attached to an object.

In the design shown the plate 1 is made as shown in Figure 1 with the name of the intersecting street as indicated by the word First at the top of the plate as indicated by the numeral 4 and with a double end arrow 55 interwoven with the word so that it will be apparent that First Street would extend in both directions from the intersection as indicated by the arrow. Below the word First is the word Blocks with the number 25 60 before it as indicated by the numeral 6 representing the length of the street by the number of blocks. The word Block is also placed on the other side of the plate with the numeral 3 before it as indicated by the 65 numeral 7 which indicates the number of blocks from the end of the street. Below these words is a space 8 in which the name of the street upon which the observer is situated is placed in large letters as indicated by the 70 numeral 9 and at the lower side of the space 8 is an arrow head 10 pointing directly downward as shown. Below the space 8 are other representations of the word Block as indicated by the numerals 11 and 12, one of which 75 will represent the length of the street by blocks and the other the number of the block from the beginning of the street. It is understood that the wording described above may be placed on both sides of the plate. 80

On the angularly disposed plate as indicated by the numeral 2 is a similar representation of the names of the streets with the names reversed so that the name of the intersecting street will be at the top and 85 the name of the street upon which you are, at the bottom.

The strap 3 may be attached to the plate as shown in Figures 2 and 3. The strap may extend across the plate in the space 90 between the words "First" and "Marion" with the words Blocks and their corresponding numbers on the straps. The supporting strap 3 may be made as shown in Figure 3 and attached to a continuous belt 13 extending around a post by rivets 14 with the inner ends of the plates held to the strap by bolts 15 and the outer ends provided with notches 16 so that the ends of the strap may be bent around and pass through the notches 95 100

to hold the plates. The ends of the strap 13 may be flanged and held by a bolt 17 as shown. The strap 3 may also be made as shown in Figure 4 with the ends bent around a post and flanged so that they may be held by a bolt 18. In the design shown in Figure 4 the ends of the straps may extend outward as indicated by the numeral 19 so that they may readily be attached to a corner of a building.

11 It will be understood that changes may be made in the construction without departing from the spirit of the invention. One of the changes may be in the design of the plate or the arrangement of the wording thereon. Another may be in the omission of the word Block with its corresponding numerals and still another may be in the use of other means for supporting the plates.

12 The construction will be readily understood from the foregoing description. To use the sign it may be attached to a post with the plates extending outward as shown in Figure 2 or attached to the corner of a building or any other suitable object and it will be observed that the wording on the plates can be very easily seen so that one may instantly determine the names of both the streets at an intersection and the number of blocks from the end of the street.

13 Having thus fully described the invention, what I claim as new and desire to secure by Letters Patent, is:—

14 In a street marking sign, two plates positioned at right angles to each other, straps extending continuously through the central portions of the plates, and means for attaching the plates to an object through the straps, both of the said plates having the names of the intersecting streets on both sides thereof with the name of the cross street in the upper position and provided with arrows pointing in both directions, the name of the street facing the sign in the lower position and with an arrow pointing downward, and in combination with the names of both the streets the number of blocks in the street, and also the number of blocks from one end of the street.
